UNITED STATES PATENT OFFICE.

RAY A. FRISBIE, OF DETROIT, MICHIGAN, ASSIGNOR TO WHITE PRODUCTS COMPANY,
OF CHICAGO, ILLINOIS, A CORPORATION OF ILLINOIS.

HOOD LATCH.

Application filed August 10, 1921. Serial No. 491,201.

This invention relates to mechanism for securing the hoods of automobiles and the like in lowered or closed position.

One of the objects of the invention is so arranging the latching devices for securing the hoods of automobiles in lowered position that they will not be subjected to the torsional movements or twisting action of the frame. Another object of the invention is the construction and arrangement of a latching mechanism that will eliminate noise or rattling of the members on which it is employed and one that may be used on cars of various designs.

Other and further objects and advantages of the invention will appear as the description proceeds.

On the drawings:
20 Figure 1 is a side elevation of a portion of the front end of an automobile showing my invention thereon;

25 Figure 2 is a vertical sectional view showing the front catch on the right side of the automobile;

Figure 3 is a side elevation showing the rear catch on the left side, parts being broken away and parts in section;

30 Figure 4 is a rear elevation of a portion of a radiator showing one of the keepers applied thereto;

Figure 5 is a plan view of a spring retaining member in position to be crimped or clamped in the retaining groove, the latch bolt being shown in section;

35 Figure 6 is a front elevation of a portion of the dash showing a modified form of one keeper member applied thereto;

Figure 7 is a vertical section of a modified form of the keeper;

40 Figure 8 is a section of a modified form of the device showing the same applied to the automobile; and

Figure 9 is a section on line 9—9 of Figure 8.

On the drawings, the numeral 10 designates the chassis frame of an automobile, on which are mounted the supports for the hood 13, as the dash structure 11 and radiator or 50 similar front end support 12, all of which are or may be of the usual or well known construction.

The dash structure comprises the cowl 14 and the transverse member or dash proper

15, to which the cowl is connected in any 55 suitable manner. The dash may be provided with a forwardly extending flange 16 and the radiator with a rearwardly extending flange 46, as is usual in such constructions.

Each half of the hood 13 comprises two 60 sections 17 and 18 hinged together along the line 19, the two halves being hinged together along the line 20 in the usual manner. A protecting member 21, which may be of sheet metal, is secured along the upper side 65 of the chassis frame member 10 and extends inwardly and has its inner edge bent upwardly to form the flange 22 arranged in spaced relation to the lower edge 23 of the hood section 18. This member 21 may be, 70 and usually is, an extension of the fender skirt. The flange 22 prevents entrance of water into the space protected by the hood. The lower edge 23 of the hood is also spaced from the member 21 for a purpose that will 75 presently appear.

The hood 13 is provided with a plurality of latches or retaining members, of which any desired number may be employed, two only being shown for the purpose of description and illustration. These retaining members may be arranged at any convenient points on the hood 13, as for instance, on the lower portions of the section 18, as shown in Figure 1. 85

Each retaining member comprises a body portion 24 having an attaching flange 25 rigidly secured thereto or, as shown, made integral therewith. The body portion 24 forms a housing which has a tubular extension 26 at its upper end extending outwardly and upwardly from the flange 25. It also has a semi-circular extension 27 at its lower end which projects inwardly and downwardly from said flange. The lower end of the 90 extension 27 is provided with a lip 28, having an elongated opening 29 therethrough in alignment with the tube 26.

A latch or holding member 30 is provided to which is secured the upper end of a latch bolt 31, which is slidably mounted in the tube 26 and in the opening 29 in the lip 28. The latch bolt is provided with a circular recess 32 (Figure 5), in which is mounted the collar or spring retaining member 33. 100 As shown in Figures 2, 5 and 8, this collar is in the form of a split ring and is secured in position by first placing it in the recess 105

spring 34^a. The tongue 55 is provided with an elongated aperture 29^a through which the latch bolt 31^a extends.

The operation of this device is substantially the same as the device shown in Figures 1 to 4.

It is thought from the foregoing taken in connection with the accompanying drawings that the construction and operation of my device will be apparent to those skilled in the art, and that various changes in size, shape and proportion and details of construction may be made without departing from the spirit and scope of the appended 15 claims.

I claim:

1. In a device of the class described, a hood, a reciprocating and rotatable latch member carried thereby, means for supporting said member adapted to permit swinging movement thereof relative to the hood, and a resilient keeper engageable by said member.
2. In a device of the class described, a hood, a reciprocating and rotatable latch member carried thereby, a keeper engageable by said member, means for supporting said member adapted to permit swinging movement thereof relative to the hood, and spring 30 means tending to move said member away from said keeper.
3. In a device of the class described, a keeper, said keeper being provided with an opening formed by striking down a tongue

or catch member from the body portion 35 thereof, a spring catch member, said members converging downwardly and means for clamping said spring member to said keeper, substantially as shown and described.

4. In a hood catch for automobiles, a body adapted to be secured in an aperture in a hood and to extend through said aperture, said body having a recess open to the interior of the hood, a spring seated in said recess, and a latch member guided in said body and actuated in one direction by said spring.

5. In a device of the class described, a hood, a reciprocating latch member carried thereby, and means for supporting said member adapted to permit swinging movement thereof in a plane longitudinally of the hood.

6. In a device of the class described, a hood, a reciprocating and rotatable latch member carried thereby, and guiding means for said member to permit swinging movement of the same in a plane longitudinally of the hood but to prevent such movement in a plane transversely of the hood.

7. In a device of the class described, a hood, a latch bolt on the hood provided with an annular recess, a collar secured in said recess by being pressed therein, and a spring seating against the collar for imparting 65 longitudinal movement to the bolt.

In testimony whereof I affix my signature.
RAY A. FRISBIE.
